UNITED STATES PATENT OFFICE.

RALPH R. EDWARDS, OF HELPER, UTAH.

SANITARY HOLDER FOR RAZOR-STROPS.

1,310,744.

Specification of Letters Patent. Patented July 22, 1919.

Application filed April 8, 1918. Serial No. 227,231.

To all whom it may concern:

Be it known that I, RALPH R. EDWARDS, a citizen of the United States, residing at Helper, in the county of Carbon and State 5 of Utah, have invented certain new and useful Improvements in Sanitary Holders for Razor-Strops, of which the following is a specification.

This invention relates to improvements in 10 razor strops and similar articles and its primary object is to provide a simple and practical container for the strop which will keep the latter disinfected and in entirely sanitary condition.

15 With the above and other objects in view as will hereinafter appear, the invention consists in the novel construction, combination and arrangement of parts hereinafter described and claimed, and illustrated in the 20 accompanying drawings in which:

Figure 1 is a side or end elevation of a razor strop holder or container constructed in accordance with my invention.

Fig. 2 is a front elevation.

25 Fig. 3 is a vertical sectional view taken on line 3—3 of Fig. 2, and

Fig. 4 is a similar sectional view taken on line 4—4 of Fig. 1.

Referring more particularly to the drawings, the numeral 1 designates a casing in 30 which is to be inclosed the ordinary razor strop 2, the latter preferably constructed of the usual leather and canvas members and being secured to a roller 3 on which it is 35 wound. The roller 3 is actuated by a spring 4 arranged within it, as shown in Fig. 3, and while any sort of spring roller may be employed, I preferably make the latter similar to the well known type of window 40 shade roller. The spring 4 tends to actuate the roller 3 to draw the strop into the casing through an opening 5 and on the free end of the strop is a handle loop 6 which is of greater length than the length of the 45 slot 5 to prevent it from passing into the casing under the action of the spring roller.

While the casing 2 may be of any desired 50 shape and construction, I prefer making it in the form of a cylinder as shown, and leave one end open to be closed by a removable circular cover 7 which may be secured in any desired manner but which, as shown in Fig. 4, is provided with an internally threaded 55 annular flange 8 adapted to engage screw threads 9 on the open end or side of the casing 1. The cover or removable side 7

and the opposite side or end of the casing are provided with centrally arranged openings to receive the journals on the ends of the spring actuated roller 3, as will be 60 seen on reference to Fig. 4. To support the casing from a hook, or the like, on a barber's chair or other support, I preferably provide a suspending link 10 provided at its upper end with a loop or eye and having at its 65 lower end a suitable swiveled connection, shown at 11, to the top of the casing 1. As shown in Fig. 4, this swiveled connection consists of a spherical head on the link 10 arranged within a stamped metal bracket 70 plate 12 suitably secured to the casing.

For the purpose of disinfecting the razor strop and keeping it in a sanitary condition, I provide on one side of the casing 1 a tank or container 13 provided with a centrally 75 arranged filling opening 14 closed by a screw plug 15 or other suitable closure. The container 13 is preferably formed from a piece of metal stamped into a concave formation and having its edge secured to the side wall 80 of casing 1, as shown at 16, whereby a portion of such casing forms one wall of the container or tank. This container 13 is preferably filled with an absorbent material 17, such as cotton or felt, adapted to be saturated with a disinfectant or antiseptic solution of any character introduced through the opening 14. To permit the fumes from 85 the disinfectant to enter the interior of the casing 1, I provide upper and lower vent tubes 18 and 19 which project from the casing into the tank or container 13 as shown in Fig. 3. Owing to this construction and the use of absorbent material 17, it will be seen that the solution or liquid will be prevented 90 from entering the casing 1 and wetting the strop. At the same time, the spaced arrangement of the tubes 18 and 19 permits of a circulation through the tank 13 and casing 1, so that as the strop is wound and unwound, the fumes from the disinfectant will 95 come in contact with the two members of the strop.

From the foregoing, it will be seen that, by the construction above described, I provide for the keeping of the strop when not in use in a substantially close container or casing where it will be kept free from dust and at the same time, I provide a simple and effective means for disinfecting or fumigating the strop each time it is used by being drawn out of or moved into the casing.

To prevent the strop from being damaged, the side walls of the slot 5 have rolled edges, as shown in Fig. 3.

While I have shown and described a preferred embodiment of my invention, I wish it understood that slight changes of shape, proportions and arrangement of parts may be resorted to within the spirit and scope of the invention as herein claimed.

10 I claim:

A device of the character set forth comprising a cylindrical casing having an opening in its bottom, a pair of vertically spaced tubes projecting outwardly from the curved 15 wall of the casing on one side at a point about midway between its top and bottom, said tubes having their inner ends communi-

cating with the interior of the casing, a concaved stamped metal member arranged over the open outer ends of the spaced tubes 20 and having its edge shaped to conform to and secured to the adjacent portions of the curved wall of the casing to provide a disinfectant container, an absorbent member in said disinfectant container, and means 25 to permit a disinfectant or the like to be applied to said absorbent member.

In testimony whereof I affix my signature in presence of two witnesses.

RALPH R. EDWARDS.
